UNITED STATES PATENT OFFICE.

SPENCER B. PRENTISS, OF WASHINGTON, DISTRICT OF COLUMBIA.

PLATEN SHIFT-KEY FOR TYPE-WRITING MACHINES.

No. 879,317.

Specification of Letters Patent.

Patented Feb. 18, 1908.

Application filed March 10, 1904. Serial No. 197,525.

To all whom it may concern:

Be it known that I, SPENCER B. PRENTISS, a citizen of the United States, residing at Washington, in the District of Columbia, have 5 invented a new and useful Platen Shift-Key for Type-Writing Machines, of which the following is a specification.

My invention relates to platen shift-keys for type-writing machines, and has for its 10 object the production of a device of this general character by means of which exponent numbers or letters may be readily produced in the writing without turning the platen for that purpose.

15 Various devices or keys have heretofore been produced for partly shifting the platen of typewriting machines so that a character may be written above the line, and it is to this class of devices that my improvement 20 belongs.

In carrying my invention into effect I provide a typewriting machine, having a platen and platen shift lever, and which may be of any known or hereafter to be devised construction, with a shift key mounted upon or carried by the platen shift lever and operative when depressed to produce a partial shift of the platen, the construction and arrangement of the key being such as to permit 25 the full movement of the shift lever and the full shift of the platen. As machines are now constructed my improvement may be made as a permanent addition upon the lever of the shift key, or it may be separately 30 manufactured as an attachment to be placed upon machines already completed and in use.

The invention is illustrated in the accompanying drawings, in which

Figure 1 is a conventional representation 40 of a typewriting machine equipped with my improvement; Fig. 2 is a side view of a shift key constructed according to my invention; Fig. 3 is a front view of the same showing in whole lines the position of the parts in their 45 operated or depressed position, and in dotted lines their position taken when the platen is shifted fully; and Fig. 4 is a detached view in perspective of the device in its idle position during full shift of the platen.

50 Referring to the drawings, A is the frame of a typewriting machine, B the platen, and C C' represent in end elevation the levers of a platen shift mechanism moving together and provided with keys c c'.

55 D is an extension for the shift lever C to which it may be secured by any suitable

means such as a collar d and set screw d'. Hinged at d² to extension D, and capable of independent motion above its normal position only, and projecting over a stop such as 60 a portion a of the machine frame, is a key member d³ having a contact piece d⁴ on its under surface. Key member d³ is limited to this independent motion above its normal position, and has a rigid connection with extension D under operative pressure downward, by reason of the lip d⁵ which extends under and engages the lower end of said extension D. The parts are so proportioned 65 that when collar d is properly adjusted the 70 key member d³ will be but a short distance above stop a, as shown in Fig. 2; and this distance may be varied according to the position above the line at which it is desired to place the exponent by merely adjusting the 75 collar. A key piece d⁵ may be provided on key member d³ as shown in Fig. 3, so that the pressure applied will always be over the stop.

The operation of the device is obvious: 80 When it is desired to write a character with an exponent, such as a⁶, B⁷, 1st, the character is struck in the usual way, then key member d³ is pressed against stop a as shown in Fig. 3, and the exponent number or letter 85 then struck which will always appear the proper distance above the line. In ordinary writing when either of the regular shift keys c c' are depressed to produce a full shift of the platen, the hinge d² will permit the extension D to go down the required distance, key member d³ resting idly on stop a, as shown in 90 Fig. 4 and by dotted lines in Fig. 3.

It will be understood that many variations 95 in form and changes in proportions of parts may be made without departing from the spirit of the invention, the form shown and described being merely illustrative, and such modifications I aim to cover by the appended claims. By such changes, which will be obvious to a skilled mechanic, the invention 100 may be adapted to any make of typewriting machine. Also, while I have shown the improvement upon the right hand member of the shift lever, it may obviously be constructed 105 reversely for the left hand member.

What I claim as new and desire to secure by Letters Patent of the United States, is—

1. In a typewriting machine, the combination 110 with a platen and a platen shift lever provided with a shift key, of a shift key member wholly mounted upon and carried by

said lever for contact with a fixed portion of the machine upon a partial movement of said lever, but constructed to permit the full shift of said platen when the first mentioned shift key is depressed.

2. In a typewriting machine, the combination with a platen and a platen shift lever, of a fixed stop, a shift key member having a hinged connection with said lever for upward motion with relation thereto and projecting over said fixed stop, the parts being so arranged that when pressure is applied to the key member said stop limits the platen shift, but when the shift lever is given its full movement said key member engages said stop and moves idly upon its hinge.

3. In a typewriting machine, the combination with a platen and a platen shift lever, of a fixed stop, a shift key member adjustably mounted upon and having a hinged connection with said lever for upward motion with relation thereto and projecting over said fixed stop, the parts being so arranged that when pressure is applied to the key member said stop limits the platen shift, but when the shift lever is given its full movement said key member engages said stop and moves idly upon its hinge.

4. In a typewriting machine, the combination with a platen and a platen shift lever, of a fixed stop, a shift key member having a hinged connection with said lever, for upward motion with relation thereto and projecting over said fixed stop, and a key piece upon said key member directly over said stop, the parts being so arranged that when pressure is applied to said key piece said stop limits the platen shift a predetermined amount, but when the shift lever is given its full movement said key member engages said stop and moves idly upon its hinge.

5. In a typewriting machine, the combina-

tion with a platen and a platen shift lever, of a shift key member having a hinged connection with said lever and projecting over a fixed portion of the machine frame, whereby when the key member is depressed said frame forms a stop to limit the platen shift, but when the shift lever is given its full movement said key member moves upon its hinge.

6. As an article of manufacture, an auxiliary shift key for typewriting machines comprising a body-portion provided with means for attachment to the platen shift lever, and a key member carrying a single key-piece and hinged to said body-portion for rigid relation therewith under pressure upon said key-piece but to move idly upon its hinge by engagement with a fixed stop.

7. As an article of manufacture, an auxiliary shift key for typewriting machines comprising a body portion provided with means for attachment to the platen shift lever, and a key member hinged to said body portion to form a rigid connection therewith under operative pressure but capable of movement upon the hinge in the opposite direction.

8. As an article of manufacture, an auxiliary shift key for typewriting machines comprising a body portion provided with a split collar and an adjustment screw for attachment to the platen shift lever, and a key member hinged to said body portion to form a rigid connection therewith under operative pressure but capable of movement upon the hinge in the opposite direction.

In testimony whereof I have signed my name to this specification in the presence of two subscribing witnesses.

SPENCER B. PRENTISS.
